TRAFFIC SPEED DEVIATION COMPUTER

John L. Barker, Norwalk, Conn., assignor, by mesne assignments, to Laboratory for Electronics, Inc., Boston, Mass., a corporation of Delaware

Filed Nov. 9, 1959, Ser. No. 851,771

20 Claims. (Cl. 235—151)

The present invention relates to a vehicular traffic speed deviation measuring or indicating system or apparatus, which in a general sense measures or responds to the amount or degree of variation between the speeds of individual vehicles of a series of vehicles in traffic proceeding along a road or a traffic lane for example, and which in a more particular sense in its preferred aspect computes a deviation representing the average departure of the individual speeds from the mean value of such speeds and provides an output representing the deviation for indicating or control purposes. More specifically in its preferred aspect the present system or apparatus computes the square of the root mean square of the various speeds and also the square of the arithmetic average of the same speeds, subtracts the latter square and takes the square root of the difference as an output representing the deviation.

The invention is described herein with particular reference to its preferred application to traffic speeds but it will be appreciated that some aspects of the computation of the deviation of a series of values in accordance with the invention may have general application to factors other than traffic speed.

The invention has particular advantage in determining the deviation in speeds of the latest desired number of vehicles proceeding in the same direction past a sampling point in a single traffic lane. Several deviation computers may be employed respectively in several adjacent traffic lanes if desired, although one such computer in one lane may serve as a sample of multi-lane traffic.

In the field of traffic control, the speed deviation of vehicle traffic on a roadway may be used as a yardstick of the quality of the traffic flow along that roadway. Speed deviation of traffic flow along a roadway may also be used as a measure of the efficiency with which vehicle traffic is passed along the roadway, with particular emphasis on restricted thoroughfares such as freeways, bridges and tunnels for example, and thus may serve as a guide in roadway design and in the monitoring of operation of such traffic facilities for example.

In determining the deviation of varying values of a given factor several mathematical formulas may be employed. Generally referred to as "sigma" or "standard deviation," one mathematical formula is presented at page 165 in "Traffic Engineering Handbook," second edition, published and copyrighted in 1950 by Institute of Traffic Engineers and Association of Casualty and Surety Companies. Here, referring in particular to speed deviation of vehicle traffic, standard deviation is expressed in the formula

$$SD = \sqrt{\frac{\sum F(x)^2}{N} - M^2}$$

where

SD means standard deviation and
M equals arithmetic average of all observations;
X equals value of a single observation;
F equals frequency of observation of one value;
N equals number of observations

The first term under the radical may be interpreted as the summation of the squares of all of the individual (X) values of speed divided by the number of such speeds.

2

Thus, with relation to vehicle speeds, standard deviation, or sigma or deviation equals the square root of the remainder after the square of the arithmetic average speed (A.A.²) of a predetermined number of vehicle speeds is subtracted from the summation of the squared same vehicle speeds divided by the same predetermined number of vehicle speeds, or root mean square speed squared (R.M.S.²).

Thus the formula may read deviation equals:

$$\sqrt{R.M.S.^2 - A.A.^2}$$

or the square root of the difference of the root mean square squared minus the arithmetic average squared.

I have used this formula in the electro-mechanical computation of speed deviation of vehicle traffic. In the preferred system the various speed readings are obtained and a speed of the last car value and a root mean square speed squared value, in the form of D.C. voltages are developed electro-mechanically and are then applied as individual inputs into the electro-mechanical computer for computation of speed deviation.

Prior estimates of and mathematical calculation of the average speed of vehicle traffic have been made in various manners employing mechanical speed determining and measuring devices and/or electronic calculating devices.

One method of determining the root mean square speed of vehicle traffic through traffic actuation, with provision for obtaining an output representing the root mean square speed squared, and an output representing the speed of the last vehicle is taught in my copending application, Serial Number 732,248, filed May 1, 1958, under the title "Traffic Monitoring System."

From one aspect the present invention provides a vehicle actuated traffic speed deviation indicating system capable of determining and indicating speed deviation currently or on a substantially continuous basis for traffic passing a given location on a roadway or traffic lane.

From another aspect the present invention relates to novel apparatus and method for determining the average speed of vehicle traffic on a roadway and for determining and indicating speed deviation of the measured speeds of vehicles in the traffic flow automatically.

My said copending application Serial Number 732,248 describes a vehicle traffic monitoring system for sensing the presence and speed of each vehicle passing a particular location in the roadway, and for indicating each vehicle speed, the root mean square speed of a predetermined number of vehicles and the volume of traffic on a roadway.

As more fully described in my said copending application, the presence of a vehicle is sensed and its road speed is evaluated through the cooperation of a radar sensing unit RS1 and a speed and volume impulse translator. The detection and speed information of each vehicle so sensed, is available in the forms of electrical output of the speed and volume impulse translator. Detection information is available in the form of closure of a normally open contact as a vehicle passes under the radar sensing unit while the speed information is available in the form of a D.C. voltage, the amplitude of which is proportional to the speed of the vehicle sensed, with 14 volts equal to 100 miles per hour, for example.

Each time a vehicle is sensed its speed is read and converted into a D.C. voltage proportional to its road speed at the moment of measurement. This D.C. voltage referred to as being representative of "last car speed," is available as one of the outputs of the speed averaging unit of the said copending application.

Another voltage, representative of the last car speed squared is also developed and several consecutive voltages

representative of several consecutive last car speed squared values are averaged by electro-mechanical averaging circuits to obtain the root mean square speed squared of the last predetermined number of vehicles passing a predetermined position. A D.C. voltage representing the root mean square speed squared (R.M.S.²) is also available as one of the outputs of the speed averaging unit of my said copending application.

According to the preferred embodiment the D.C. voltage proportional to the last car speed and the D.C. voltage representing the root mean square speed squared are applied to a deviation unit. The deviation unit receives the D.C. voltage proportional to the last car speed and electro-mechanically provides a D.C. voltage output representing the arithmetic average speed squared of the last predetermined number of last car speeds; the output representing the arithmetic average speed squared is based on substantially the same vehicle speeds as the root mean square speed squared output of the speed averaging unit all of these output voltages being referred back to a common reference level.

The D.C. voltage representing the arithmetic average speed squared, $\overline{A.A.}^2$, is subtracted from the root mean square speed squared, $\overline{R.M.S.}^2$, in a difference computer circuit in the deviation unit providing a difference voltage representing deviation squared. Through electro-mechanical computation a D.C. voltage is obtained in the form of an output which may be used to drive a motor to indicate speed deviation on a calibrated scale or such output may be made to operate a circuit at a selected or selectable value of speed deviation.

It is therefore an object of the present invention to provide apparatus for use in a traffic monitoring system for providing an electrical output representing the root mean square of the speeds squared of a last predetermined number of vehicles passing a predetermined position on a traffic lane or roadway and for providing an electrical output representing the arithmetic average of the speeds squared of the same last predetermined number of vehicles and deriving therefrom speed deviation in the form of an electrical output.

It is another object to provide a traffic speed deviation measuring or indicating system that automatically determines speed deviation of vehicle traffic passing a predetermined position on a traffic lane or roadway.

A further object is to provide a vehicle actuated traffic speed deviation indicating system that provides speed deviation of the last predetermined number of vehicles so actuating the said traffic speed deviation indicating system.

It is also an object of the invention to provide a deviation unit for cooperation with a speed averaging unit having a last car speed output signal and a squared root mean square output signal, to determine the speed deviation of a desired number of vehicles or cars.

It is further object of the invention to provide an improved deviation computer.

Other objects will become more apparent from a reading of the following detailed description with reference to the accompanying drawings where:

FIG. 1 represents, in block form, one form of traffic speed deviation measuring or indicating system, in accordance with the present invention;

FIG. 2 represents, partly in block and partly in schematic circuit form, an alternate form of speed averaging unit that may be used as part of a complete traffic speed deviation computer in accordance with the present invention, and

FIG. 3, including FIG. 3a and FIG. 3b, illustrates, in schematic circuit form the preferred embodiment of the deviation unit.

Referring to FIG. 1 in more detail, a block diagram of one form of traffic speed deviation indicating system is presented including a vehicle detection and speed sensing unit, that may be in the form of the Radar Sensing Unit,

block 10, an associated Speed and Volume Impulse Translator, block 11, a Speed Averaging Unit, broken line block 12 and a Deviation Unit, broken line block 13.

The Radar Sensing Unit may be similar to the Radar Sensing Unit RSI disclosed in my copending application Serial Number 732,248, filed May 1, 1958, under the title "Traffic Monitoring System" which detects the presence of a vehicle on the roadway and thereafter senses its speed giving a composite signal output indicative of vehicle detection and speed combined.

The Speed and Volume Impulse Translator, may be similar to the Speed and Volume Impulse Translator disclosed in my said copending application Number 732,248, which translates the composite output of the Radar Sensing Unit into two separate informations. One output of the Speed and Volume Impulse Translator is in the form of a normally open contact which closes representing detection of a vehicle and a second output in the form of a D.C. voltage proportional to the speed of a vehicle or speed indication.

The two outputs of the Speed and Volume Impulse Translator are in usable form for input into a Speed Averaging Unit, represented by broken line block 12. Broken line block 12 may represent a Speed Averaging Unit similar to the Speed Averaging Unit described and illustrated in my said copending application Number 732,248 which receives the outputs from a Speed and Volume Impulse Translator and provides therefrom D.C. voltage outputs individually representing the speed of the vehicle detected (last car speed) and the root mean square speed squared ($\overline{R.M.S.}^2$) where a last car speed of 0 to 100 miles per hour is represented by a D.C. voltage of 0 to +10 volts, for example.

Within broken line block 12 is a functional block diagram of a speed averaging unit basically similar to the functional block diagram presented in my said copending application representing the disclosed Speed Averaging Unit. The present functional block diagram differs from the functional block diagram in my said copending application in that a relay, AIN is shown in the Null, block 26; a relay Ab is shown in Gate, block 24; and broken lines 37b and 41 are extended from the block diagram. The relay AIN represents that a relay, labeled AIN in the circuit diagram in my said copending application, is operated by the Null 26 while relay Ab represents that a relay, labeled Ab (along with a parallel connected relay Aa) in the circuit diagram in my said copending application, is operated as Gate 24. The broken line 37b indicates that the Null 26 is used to operate "Not" Gate 43 and Gate 45 in broken line block 13 and broken line 41 indicates that block 22, in broken line block 12, and block 40, in broken line block 13, are adjusted to select the same number of cars to be averaged.

FIG. 2 herein illustrates, partly in block and partly in circuit form, a simplified form of another type of speed averaging unit that may be used in association with block 13 of FIG. 1 thus providing an alternate form of traffic speed direction indicating system. The blocks 10 and 11 in FIG. 2 are similar to the blocks 10 and 11 in FIG. 1 while the remainder of FIG. 2, the simplified form of a speed averaging unit, may be employed to provide outputs for input into block 13, the deviation unit. The outputs of the speed averaging unit, 12, of FIG. 1 for input into block 13 are substantially in the same form as the outputs of the speed averaging unit of FIG. 2. Thus FIG. 1 represents one form of traffic speed deviation indicating system while the combination represented in FIG. 2 plus a deviation unit, represented by block 13 in FIG. 1, represents another form of traffic speed deviation indicating system.

Block 13 represents a deviation unit and is illustrated in full schematic circuit form in FIG. 3 including FIG. 3a and FIG. 3b.

In point of time, the detector impulse output from the

speed and volume impulse translator is applied to the speed averaging unit followed shortly thereafter by the speed indication output. Thus the detector impulse is applied to speed averaging unit where the length of the detector impulse is used to determine the time the detected vehicle will be at a predetermined position relative to the radar sensing unit. This predetermined position is at a position approximately at a 60 degree angle between the vertical from the sensing unit to the roadway and the line between the sensing unit and the vehicle.

With the detector impulse applied to block 15, Time Delay to 60° Point, and Speed Indication applied to Gate 17 the speed information, in the form of D.C. voltage, is fed via Gate 17, to Calibration Circuit 18, and to L.C. Electrical Storage, 19, and at a time as controlled by block 15, Gate 17 is operated via lead 16 to cut off the voltage applied therethrough.

The speed indication in the form of a D.C. voltage whose amplitude of from 0 to +14 volts representing 0 to 100 miles per hour, is applied to a calibration circuit, block 18, which adjusts the speed indication voltage so that a scale of 0 to +10 volts equals 0 to 100 miles per hour. This last vehicle speed (L.C.) indication of 0 to +10 volts is applied to an L.C. electrical storage, block 19. Block 20, L.C. Mechanical Storage, is driven by means of a phase sensitive reversible servo motor to match the value stored in block 19 so that a voltage representative of the speed of the last vehicle or L.C. will be stored both electrically, as for example by a charge on a capacitor representing L.C. and mechanically, as for example, by positioning the arm of a potentiometer so that with a fixed voltage applied through the resistance of the potentiometer the voltage at the arm of the potentiometer will be substantially equal to the value of the charge on the capacitor and thus each voltage value will be representative of the L.C.

The block 20 may include a servo amplifier and a servo motor which may be used to position the arm of the potentiometer of the L.C. mechanical storage, typical circuitry of which is fully disclosed in my said copending application Number 732,248.

A squaring potentiometer is provided, block 21, with the arm of the squaring potentiometer connected to the arm of the L.C. mechanical storage potentiometer so that as the arm of the potentiometer in block 20 is driven to match electrical storage, the arm in block 20 is driven to a corresponding position and an output from block 21 is obtained representing the last vehicle speed squared or $\overline{L.C.}^2$.

Thus when the gate 17 operates to cut off the voltage applied through the gate, as controlled by time delay 15, the L.C. value in block 19, having been recalibrated by block 18, represents the speed of the last vehicle and block 20 is driven to match the value of block 19 thus mechanically storing the L.C. speed while block 21 is driven with block 20 to provide an output representing the square of the last vehicle speed or $\overline{L.C.}^2$.

The output of block 21, $\overline{L.C.}^2$, is applied to a block 22, Number of Cars Averaged Circuit. Block 22 may, for example, include a voltage divider which may be adjustable so that the number of car speeds averaged may be adjustable, as desired. Also applied to the block 22 via lead 31, is the output voltage of block 29, a voltage representing the old root mean square speed squared ($\overline{R.M.S.}^2$) so that the last vehicle speed squared may be averaged with the root mean square speed squared and a new root mean square speed squared may be applied to New $\overline{R.M.S.}^2$ Electrical Storage, block 23.

As block 20 and block 21 are being adjusted to a new value the electrical storage in block 23 is being adjusted to a new value also.

When the value of the output of block 20 or the L.C. mechanical storage equals the value of the output of block 19, or the L.C. electrical storage, a null (block 26)

between the two outputs is reached which operates a relay, here indicated as relay AIN. A gate block 24 including a second relay, here indicated as relay Ab, is operated by null, 26 via lead 25 and 37a. At this moment since the block 21 has also been adjusted to a new $\overline{L.C.}^2$ value, the block 23 has been adjusted to a new $\overline{R.M.S.}^2$ electrical storage value.

Operation of the gate, block 24, via lead 37a from the block 26, permits adjustment of the $\overline{R.M.S.}^2$ Mechanical Storage, block 29.

The block 23, new $\overline{R.M.S.}^2$ electrical storage may, for example, include a capacitor capable of storing and holding an electrical charge representative of the $\overline{R.M.S.}^2$ while the block 29, $\overline{R.M.S.}^2$ mechanical storage may, for example, be in the form of a potentiometer with an arm adjustable through a servo mechanism so that the value of the voltage output at the arm of the potentiometer may be adjusted to equal the value of the voltage charge on a capacitor in block 23.

The block 20 and the block 29 may, for example, each include a servo amplifier section and a phase sensitive, bidirectional servo motor which may be employed to drive the movable arms of the respective potentiometers to a position where the output of the respective blocks, which is the voltage at the respective arm of the potentiometer, is equal to the input from the previous block or one servo amplifier may be employed and switched as desired between the servo motors of the respective blocks as illustrated in my said copending application Number 732,248.

Upon reaching a null between the output of block 23 through gate 24 and the output of block 29, the null, block 30, for example, may operate to open this circuit 35 at gate 24 and reset the mechanism preparatory for receipt of the next succeeding detector impulse and speed indication.

Thus out of the block 12 an output representing the speed of the last vehicle (L.C.) 35, is obtained from block 20 and an output representing the root mean square speed squared ($\overline{R.M.S.}^2$) 36, is obtained from block 29 with both outputs applied to block 13, the deviation unit as here illustrated.

Last vehicle speed information (L.C.), lead 35, is applied to Number of Cars Averaged Circuit, 40 in the deviation unit, broken line block 13. Broken line 41 between block 22 and block 40 is to indicate that both number of cars averaged circuits are adjusted to select the same numbers of cars to be averaged. Also applied to block 40 is a voltage from Arithmetic Average Speed Mechanical Storage, block 46, via lead 42, representing the old Arithmetic Average Speed from the mechanical storage. Thus the speed of the last vehicle, L.C. via lead 35, is applied to the number of cars averaged circuit 40 and is averaged with the old arithmetic average speed and applied through "Not" gate 43 to block 44 the new Arithmetic Average Speed Electrical Storage (A.A.).

It should be observed that the "not" gate 43 and gate 45 are both connected, by broken line 37b and lead 25 to null, block 26. "Not" gate 43 is the inverse of gate 45, that is, although both gates are operated simultaneously via lead 37b, "not" gate 43 is closed when gate 45 is open and vice versa.

Concurrently as block 20 L.C. mechanical storage, is being adjusted, prior to operation of the null relay AIN, the L.C. information is being fed via lead 35 to block 40, through block 43 and into block 44 so that block 44 is being adjusted to a new value through "not" gate 43 before the null occurs between blocks 19 and 20.

When the null between blocks 19 and 20 occurs operation of null relay, AIN, reverses the condition of the gate 45 so that block 46 may be adjusted to the new value now on block 44 and also reverses the condition of the "not" gate 43 so as to stop further adjustment of block 44 from block 40.

The new Arithmetic Average Speed Electrical Storage data is now transferred to the Arithmetic Average Speed Mechanical Storage through closure of gate 45. Thus the A.A. mechanical storage, block 46 is driven to watch the value of the new A.A. electrical storage block 44 at substantially the same time as R.M.S.² mechanical storage block 29, is driven to match new M.R.S.² electrical storage block 23.

The Arithmetic Average Speed Squared, A.A.², block 47 is linked to block 46 so that as the arm of the potentiometer in block 46 is adjusted to a new position the arm of the potentiometer blocked block 47 is also adjusted to a new position relative to the position of the arm in block 46.

As illustrated in the circuit form partly in FIG. 3a and partly in FIG. 3b block off by broken line block 46, the block 46 in FIG. 1 may include a chopper coupled to a servo amplifier which drives a servo motor and a potentiometer with the arm of the potentiometer mechanically connected, through suitable gearing, to the servo motor, which is illustrated as a phase sensitive, bidirectional motor.

The output of block 47, a voltage representing the arithmetic average speed squared A.A.² is fed via lead 47a to block 48, a difference computer.

The output R.M.S.² of block 29 of the speed average unit, 12, is also applied via lead 36 to the deviation unit, 13, into block 48 so that the R.M.S.², in the form of a voltage representing the root mean square speed squared, which is on the same base as the A.A.², and the A.A.² may be subtracted from each other so that the difference voltage may be obtained, which represents speed deviation squared, which may be mechanically stored in block 49. Block 49 in FIG. 1 may include a chopper coupled to a high gain servo amplifier assembly, which drives a servo motor and a potentiometer, the arm of which is mechanically connected, through suitable gearing to a phase sensitive, bidirectional motor, as illustrated partly in FIG. 3a and partly in FIG. 3b block off by broken line block 49.

Block 50 may include a potentiometer, the arm of which is linked to the arm of a second potentiometer, in block 49 so that the arm in block 50 is positioned on its associated resistance corresponding to the position of the arm in block 49 on its associated resistance with the output of the arm in block 50 applied to the resistance of the potentiometer in block 49. Thus as the output of block 49 represents deviation squared, the output of block 50 is a voltage representing the square root of the deviation squared and thus the value of the output at lead 50a is the traffic speed deviation which may be displayed on a meter suitably connected to the output as for example meter 232 in FIG. 3b.

FIG. 2 illustrates, partly in block and partly in schematic form a simplified form of speed averaging unit that may be used in association with the deviation unit to form a traffic speed deviation indicating system.

The speed averaging unit illustrated in FIG. 2 differs somewhat from the speed averaging unit disclosed in my said copending application Number 732,248 although the radar sensing unit, (R.S.U.), 10, may be similar to the radar sensing unit R.S.I. described in my said copending application and previously mentioned herein, and the speed and volume impulse translator (S.V.I.T.), 11 may be similar to the speed and volume impulse translator described in my said copending application and previously mentioned herein.

The composite signal output of the radar sensing unit, block 10, will be fed to the speed and volume impulse translator, block 11, as a vehicle passes under the radar sensing unit. The composite signal is translated into a detector impulse which operates a relay 170, to close a pair of normally open contacts A, in block 11, for example, and into speed indication as a D.C. output via

lead 88 of 0 to +14 volts D.C. representing 0 to 100 miles per hour. The speed indication signal is applied to a potentiometer 60 and arm 61 picks off a percentage of the signal.

5 Since the vehicle speed will be measured at an angular position of approximately 60°, between the vertical, from the sensing unit to the roadway and line between the sensing unit and the vehicle, and since the vehicle's speed as stored on capacitor 64 should be calibrated 0 to +10 volts equal to 0 to 100 miles per hour speed; the setting of arm 61 is such as to compensate for the angular position of the vehicle at the time contact T1 opens the circuit, as will be described later.

Although an angular position of 60° is the preferred position such angular position is not limited to 60° as the arm 61 may be positioned for recalibration of speed taken at other angular positions as desired.

Thus the signal applied via lead 88 is recalibrated before being applied through diode 62 and contact T1 to capacitor 64. Capacitor 64 may be called a last car speed electrical storage since with contact T1 of relay T closed, the voltage picked off at arm 61, which represents the speed of the last car, is applied to and does charge capacitor 64 to such voltage. The resistance 63 provides a bleed off path so that capacitor 64 may discharge somewhat if the speed indication of the previous vehicle was higher than the speed indication of the present vehicle thus providing for controlled charge and discharge to assure that the charge placed on the capacitor 64 is substantially equal to the voltage at arm 61 which represents the speed of the vehicle.

Operation of the speed averaging unit of FIG. 2 commences with energization of the relay 170 resulting in closure of contact A. The detector impulse, which is inversely proportional to the speed of the vehicle sensed maintains the relay 170 energized for such time period.

Closure of contact A of relay 170 in block 11 completes a pull-in circuit for relay R from a common ground through contact A, normally closed contact S1 of de-energized relay S, the coil of relay R to D.C. supply.

Relay R closes its contacts R1, R2 and R4 thus completing a holding circuit through contacts A, and R1.

The opening of contact R3 and closure of R2 opens the charging circuit for capacitor CT and provides a bleed off path through adjustable resistor 51, after having been charged from a D.C. supply, through adjustable resistor 52, and contact R3. As soon as the charge on capacitor CT reduces somewhat the relay T pulls in from D.C. supply through the coil of relay T, contact R2, adjustable resistor 51 to ground.

The relay S, upon energization, via contact R4 opens its contact S1 and closes its contacts S2 and S3. Closure of contact S2 provides a holding circuit for relay S from D.C. supply, contact S2, normally closed contact V4 of relay V to ground.

Closure of contact S3 completes a pull-in circuit for relay V but relay V is a delay action relay, the delay being on pull-in so that before the end of the delayed pull-in period, energized relay T opens its contacts T2 thus breaking the pull-in circuit of delayed relay V.

Energized relay T closes its contacts T1 to permit capacitor 64 to assume the potential at arm 61 on potentiometer 60.

65 At termination of the detector impulse by the speed and volume impulse translator, the relay 170 becomes deenergized and its contact A opens thus opening the holding circuit for relay R. Deenergized relay R releases and opens its contacts R1, R2, and R4 and closes its contact R3.

Relay R cannot now pull-in again so long as relay S remains energized since contact S1, in the pull-in circuit of relay R, is held open by now energized relay S. This prevents any succeeding false operations of contact A due to a succeeding salient reflection on a long vehicle

or an impulse from an exceedingly close spaced second vehicle from getting into the sequence of speed averaging until the first measurement is assimilated in the averaging unit, as herein described.

The period of energization of relay R is substantially equal to the period of closure of contact A, which periods are both inversely proportional to the speed of the vehicle detected. The length of the period of energization of relay R determines the amount of discharge of timing capacitor CT through timing resistance. The amount of discharge of capacitor CT determines the amount of time necessary for controlled recharging of the capacitor. The amount of time necessary for recharging of capacitor CT determines the time delay between the opening of the energizing circuit for relay T and the fall out of relay T.

Thus the speed of the vehicle as it passes under the sensing unit is utilized to determine when the vehicle will be in a certain desired position with relation to the sensing unit. Since the detector impulse is inversely proportional to vehicle speed, a slow moving vehicle will provide a longer detector impulse and hold relay R energized for a longer period of time thus providing for greater discharge of capacitor CT and longer delayed fall out of relay T than a more rapid moving vehicle. Thus the slower moving vehicle is given more time to arrive at a desired position, than a more rapid moving vehicle is given to arrive at the same position.

When relay R becomes deenergized, at the end of the detector impulse, contact R3 is closed and provides a circuit to charge capacitor CT from D.C. supply, through resistor 52, contact R3 to capacitor CT to ground while capacitor CT is also being charged from D.C. supply through the coil of relay T to capacitor CT to ground. When contact R3 is first closed, after being held open by relay R, the voltage across relay T will be sufficient to maintain relay T energized although the energizing circuit for relay T has been opened. When the charge on capacitor CT increases to sufficient value so that the voltage across relay T can no longer maintain the relay energized, relay T drops out and reverses its contacts, contact T1 becoming open and contact T2 becoming closed.

Upon closure of contact T2 the pull in circuit for relay V is completed from D.C. supply through the coil of relay V, contact T2, contact S3, contact X3 to ground, and, after a short delay the relay V pulls in and opens its contacts V1, and V4 and closes its contacts V2 and V3.

Closure of contact V3 provides a holding circuit for relay V while closure of contact V2 provides a bleed off circuit through adjustable resistor 54 for capacitor CW, which capacitor became fully charged from D.C. supply through the adjustable resistor 53, contact V1 to capacitor CW and from D.C. supply through the coil of relay W to capacitor CW with capacitor CW returned to ground.

With capacitor CW discharged somewhat relay W becomes energized and opens its contact W1 to open the ground connection to the servo amplifier of block 90 and closes contact W2 thus connecting the chopper, block 68 to the servo amplifier through coupling capacitor 69. The chopper, block 68 may be similar to the chopper, block 68a and each may be similar to the chopper schematically illustrated in FIG. 3a blocked off by a broken dotted line block labeled 68'. The servo amplifier, block 90 may be similar to the servo amplifier block 90a and each may be similar to the servo amplifier schematically illustrated in FIG. 3a blocked off by a broken dotted line block, labeled 90' except the servo amplifier in block 90 and 90a do not have their respective outputs shorted out as illustrated in FIG. 3a at junction 101, via contact 45a.

With the opening of contact T1 the charge on capacitor 64 remains and such charge is applied to the grid 65 of cathode follower 66.

The amount of power drawn by cathode follower 66 is proportional to the potential applied to grid 65 so that the voltage on lead 67, which is a fixed percent of the power drawn by the cathode follower 66, is proportional

to the potential on grid 65 which is equal to the charge on capacitor 64 which charge represents the speed of the last vehicle.

The voltage on lead 67 is applied to a chopper, block 68 and such voltage is employed as a reference to which a voltage on lead 70 may be adjusted by operation of a two phase bi-directional servo motor, block 91 which is connected through suitable gearing to the arm 71 of potentiometer 71/72.

With +10 volts D.C. applied through resistor 72, the voltage at arm 71 will be a fraction of the +10 volts according to the position of the arm 71 relative to the extremes of the resistor 72. For example, with the arm 71 at a point three quarters of the way up from the bottom of the resistor, a voltage of 7.5 volts which is three quarters of the total applied voltage, will be applied at arm 71.

When the voltages on leads 70 and 67 are unequal this difference is sensed by the chopper 68 and the difference voltage is passed by capacitor 69 in the form of an alternating current (A.C.) to the servo amplifier, 90 via contact W2.

The relation between the two voltages, on leads 67 and 70, is expressed in the phase of the A.C. passed by capacitor 69. The relationship of the phase of the A.C. passed by capacitor 69 with reference to the A.C. operating the chopper and the servo motor, block 91, which is substantially the same A.C., determines the direction of rotation of the servo motor resulting in repositioning of arm 71 of potentiometer 71/72. The servo motor, block 91 is substantially the same as servo motor, block 91a

and both may be similar to the servo motor illustrated in FIG. 3b blocked off in broken line 91'. As explained below this motor may be a two phase, bi-directional motor.

Thus the arm 71 will be driven to a position on resistance 72 through which is applied a 10 volt D.C., so that the voltage at arm 71 which is applied to the chopper 68 via lead 70 will be equal to the voltage applied to chopper 69 via lead 67.

With the two applied voltages, via leads 67 and 70 substantially equal there will be no output from the chopper 40 and therefore will be no input into the servo amplifier all as described and illustrated in FIG. 3.

The voltage at arm 71 is applied through the resistor 74 of potentiometer 73/74 and the arm 73 may be linked mechanically to the arm 71 so that as arm 71 is positioned on resistor 72 the arm 73 is positioned on resistor 74 relative to the position of arm 71 on resistance 72.

Thus the potentiometer 73/74 may be referred to as a squaring potentiometer since the fraction of the ratio between the total applied voltage (+10 v.) and the voltage at arm 73 will be the square of the fractional position of the arm 71 on the resistor 72.

Thus the voltage at arm 71, since the arm will be driven to a position where the voltage at arm 71 will equal the voltage at lead 67, which will equal the charge on capacitor 64, will represent the speed of the last vehicle or L.C. Since the voltage of arm 71 represents the speed of the last vehicle then the voltage at arm 73 may represent the speed of the last vehicle squared or $L.C.^2$.

The output via lead 35 represents the last vehicle speed or L.C. and is in substantially the same form as the output represented by lead 35 in the block diagram in FIG. 1.

The voltage at arm 73, representing the last vehicle speed squared ($L.C.^2$) is fed through resistor 75 to junction 76. Also applied to junction 76 is a voltage from arm 79 of potentiometer 79/80 through lead 78, adjustable resistance 77 to the junction 76. The voltage on arm 79 corresponds to the old root mean square speed squared of the last predetermined number of vehicles excluding the present last car speed all as described below. The resistors 75 and 77 and junction 76 form a voltage divider at junction 76. Depending upon the ratio between the value of the resistances 75 and 77 and the value of the voltages applied at arms 73 and 79 respectively a voltage is applied via junction 76, contact X1 to the capacitor 85

equal to the new root mean square speed squared (R.M.S.²) of the last predetermined number of vehicle speeds sensed, including the present last car speed.

When the relay W became energized, contact W4 was opened and contact W3 was closed. This provides a controlled bleed off circuit for the capacitor CX to thereupon energize relay X after a time delay. The delay on relay X pull in, after energization of relay W may be somewhat less than one second, for example, to allow sufficient time for the repositioning of arm 71 and thus the repositioning of arm 73 and the adjustment of the charge on capacitor 85 before relay X pulls in.

When relay X pulls in from the D.C. supply through the coil of relay X contacts W3, adjustable resistance 55 to ground, contact X1 is opened and contact X2 is closed. Contact X3 in the holding circuit of relay V is also opened.

With contact X3 open relay V becomes deenergized and opens its contacts V2 and V3 and closes contacts V1 and V4. Closure of contact V1 provides for controlling charging of capacitor CW to time a delayed fallout of relay W.

The delayed fallout of relay W ensures that sufficient time has occurred to reposition the arm 71 so that the voltage at arm 71 via lead 70 and the voltage via lead 67 have been adjusted so that the voltages are substantially equal.

Upon deenergization of relay W contacts W2 and W3 open and contacts W1 and W4 close. Closure of contact W4 provides for controlled charging of capacitor CX to time a delayed fallout of relay X.

During energization of relay X contact X2 is closed and the voltage charge on capacitor 85 is applied to the chopper, 68a, which compares the voltage at arm 79 of potentiometer 79/80, which is fed via lead 78 to chopper 68a, with the voltage charge on capacitor 85. Any difference in voltage is sensed and is passed by capacitor 69a, as an A.C. to the servo amplifier, 90a, which in turn amplifies the A.C. and feeds the servo motor 91a. The servo motor 91a is driven according to the phase of the A.C. passed by capacitor 69a with reference to the A.C. operating the chopper 68a and the motor 91a. The arm 79 of potentiometer 79/80 is driven to a position on resistor 80 where the voltage at arm 79 is substantially equal to the voltage charge on capacitor 85 and both voltages represent the root mean square speed squared (R.M.S.²) of the last predetermined number of vehicle speeds.

When both voltages applied to chopper 68a are substantially equal there is no input into the servo amplifier and the motor stops operating.

Thus the arm 79 has been repositioned so that the voltage on arm 79 is substantially the same as the charge on capacitor 85.

The dual potentiometer arrangement 81/82 and 79/80 is similar to the dual potentiometer arrangement 71/72 and 73/74. A D.C. voltage of +10 volts is applied to resistor 82 of potentiometer 81/82 and the arm 81 is positioned mechanically on the resistor 82 corresponding to the position of arm 79 on its resistor 80. The voltage at arm 81, which is a fraction of the applied +10 volts, the fraction being equal to the position of the arm 81 intermediate the ends of the resistor 82, is applied to resistor 80 and the voltage at arm 79, which is in a corresponding mechanical position on resistor 80, may be considered the square of the voltage at arm 81, as a fraction of the total.

Thus the potentiometer 79/80 may be referred to as a squaring potentiometer since the fraction of the radio between the total applied voltage (+10 v.) and the voltage at arm 79 will be the square of the fractional position of the arm 81 on the resistor 82.

Thus the output of arm 79 via lead 36 is a D.C. voltage that represents the R.M.S.² speed and is substantially equal to the charge on capacitor 85.

When the relay X becomes deenergized the relay sequence terminates and the speed averaging unit returns to rest.

Thus it has been described that a D.C. voltage output on lead 35, representing the speed of the last vehicle and a D.C. voltage output on lead 36, representing the root mean square speed squared may be obtained in a manner somewhat different than that described in my said copending application Number 732,248 and these outputs may be applied to the deviation unit, described below to provide an alternate form of traffic speed deviation system, the present invention herein.

10 It should be noted that the pull-in circuit for the relay R includes a "break" contact of relay S so that if relay S is energized relay R cannot again be energized if the relay R had previously become deenergized as by termination of the detector impulse.

15 It should also be noted that due to the sequential operation of the relay assembly a second detector impulse may cause energization of the relay R and initiate a second cycle of operation prior to the complete termination of the original cycle without interfering with normal completion of the cycle then in progress.

Thus a simplified form of speed averaging unit, employing a timed sequential relay operation has been described from which unit is obtained the speed of the last car in a D.C. voltage based on 0 to +10 volts representing 0 to

20 100 miles per hour and a voltage representing the R.M.S.² speed for a predetermined number of last vehicle speeds through outputs 35 and 36 respectively.

If, for example, a traffic speed deviation system would include a speed averaging unit similar to that just described with reference to FIG. 2 the relay DX of the deviation unit, illustrated in FIG. 3a may be energized the same time relay X is energized and could be connected so that the coil of relay X and the coil of relay DX are connected in parallel or may be connected so that the energizing circuit of relay DX includes a "make" contact of relay X. The latter proposed circuitry may include a source of power, as for example a D.C. supply, connected to one side of a "make" contact, as contact X4 in phantom form, for example, the other side of contact 35 X4 connected to one side of the coil of relay DX (of FIG. 3a) and the other side of the coil relay DX returned to a common ground.

Operation of the deviation unit, schematically illustrated in its preferred form in FIG. 3a and FIG. 3b, will 45 now be explained relative to its operation in a traffic speed deviation indicating system.

Because of the size and complex circuitry of the deviation unit the circuit drawing includes two figures, FIG. 3a and FIG. 3b. Certain leads interconnect between FIG. 50 3a and FIG. 3b and these leads are identically labeled and extend to the edge of the respective drawings thus indicating they are interconnected between the figures to a lead identically labeled.

The power supply for the deviation unit, in FIG. 3 is 55 generally represented by a triangle, in FIG. 3b representing +300 volts D.C. for example; a circle labeled +10 representing +10 volts D.C. for example; a plus in a square representing +155 volts D.C., for example; a minus in a circle representing -10 volts D.C. for example, and two closed circles labeled + and - A.C., representing a 60 cycle per second 120 volt A.C. source, for example.

Speed information, such as the speed of the last vehicle (L.C.) and the root mean square speed squared, 60 (R.M.S.²) in the form of D.C. voltages similar to the voltages developed and applied as outputs of the speed averaging unit of my said copending application Number 732,248 and in the form of speed averaging unit illustrated in FIG. 2 herein are illustrated as being applied to the deviation unit via leads 35 and 36 respectively in FIGS. 3b and 3a respectively.

Coordination of operation between the speed averaging unit and the deviation unit is obtained through controlled operation of the relay DX, illustrated in FIG. 3a, by the 75 speed averaging unit. Normally relay DX is maintained

deenergized with both its contacts 43a and 45a closed. Last car speed information, in the form of a D.C. voltage with 0 to +10 volts representing 0 to 100 miles per hour speed, is applied through lead 35, FIG. 3b, resistance 102 to a junction 103. This last car speed signal applied to junction 103 is modified somewhat by action of a voltage divider including adjustable resistance 120 and associated resistance 122 and the resistance 102 connected to junction 103, as more fully described below. With contact 43a closed, this modified signal is applied via lead 104 to FIG. 3a via contact 43a, lead 105 to the storage capacitor 44a, which represents the new arithmetic average speed electrical storage.

The contact 45a supplies a ground connection to a junction 101 in the servo amplifier and effectively grounds any signal that may be applied to the junction 101. This prevents the servo amplifier from "floating" and prevents amplified electrical noise from being applied to drive the servo motor to erroneous settings. This is one method of control that may be used, other methods well known to those skilled in the art, may be used for control of the servo amplifier.

The broken line box 43 and the broken line box 45 in FIG. 3a illustrates one type of "not" gate and gate respectively that may be found in the block diagram in blocks 43 and 45 respectively in FIG. 1.

The broken line box 44 in FIG. 3a illustrates one type electrical storage such as may be found in the block diagram in block 44 in FIG. 1. The charge on the capacitor 44a is applied through resistance 106 to contact 107 of chopper 108.

The broken line box 48 includes circuitry that may be included in block 48 in FIG. 1 while broken line box 49 in FIG. 3a includes part of the circuitry that may be included in block 49 in FIG. 1. The remainder of the circuit components included in block 49 in FIG. 1 may be seen in broken line box 49 in FIG. 3b.

The broken line box 46 in FIG. 3a includes part of the circuitry that may be included in block 46 in FIG. 1 while the remainder of the circuit components included in block 46 in FIG. 1 are illustrated in broken line box 46 in FIG. 3b.

Broken lines boxes 47 and 50, in FIG. 3b, include circuitry that may be included in block 47 and 50 respectively in FIG. 1 while the lead labeled (42) in FIG. 3b, between broken line boxes 47 and 40 may illustrate the lead 42 in block form FIG. 1. Broken line box 40, in FIG. 3b includes circuitry that may be included in block 40 in FIG. 1.

In FIG. 3b, at terminal 160, a +10 volt D.C. supply is applied through resistance 114 of potentiometer 114/115. The value of the D.C. voltage at arm 115, with respect to ground, is substantially the same as the value of the voltage at junction 110, with respect to ground.

The voltage at junction 110 is applied via lead (42) through part of the voltage divider including resistance 122, part of adjustable resistance 120 to selector arm 121 to junction 103. Also applied to junction 103 through resistance 102 is a voltage representing the last car speed via lead 35. The resultant voltage of the voltage divider action is applied via lead 104, to FIG. 3a, contact 43a, lead 105 to capacitor 44a. This charge applied to capacitor 44a represents the new arithmetic average speed of the last predetermined number of vehicles.

The output of potentiometer 114/115, the arithmetic average speed mechanical storage, applied to junction 110 is also applied to lead 116 to FIG. 3a, through impedance 117 and resistance 118 to contact 109 of chopper 108. The charge on capacitor 44a is applied through resistance 106 to contact 107 of chopper 108.

The voltage potential on contact 109 of chopper 108 represents the old arithmetic average speed while the voltage potential on contact 107 of chopper 108 represents the new arithmetic average speed; that is the voltage at

arm 115, the old arithmetic average speed, and the voltage at lead 35, the last vehicle speed as modified via the voltage divider action and applied via lead 104, etc., to the capacitor, to the contact 107.

The chopper 108 is operated from a 60 cycle per second alternating current (A.C.) supply and arm 111 alternately connects between contact 107 and contact 109. The difference voltage between the potentials at contacts 107 and 109 is sensed at capacitor 113 and passes as an A.C. voltage whose amplitude is equal to the difference between the potentials applied to contacts 107 and 109 and whose electrical phase is determined by the relationship between the two different potentials.

When the voltage potentials at contacts 107 and 109 are substantially the same, the difference voltage will be zero and without change in potential applied to capacitor 113. Thus capacitor 113 senses a D.C. potential which is substantially blocked.

The amplitude of the A.C. voltage substantially equals any difference between the two potentials at 107 and 109. The electrical phase of the difference potential appearing as an A.C., is determined by the relationship between the two potentials with respect to the higher of the two potentials. Thus the electrical phase of the A.C. is determined by whichever is the higher potential and thus determines the direction in which the arm 115 must be driven on the resistance 114 so that the voltage at arm 115 or contact 109 is made to be substantially equal to the voltage charge on the capacitor 44a or contact 107.

The 60 cycle per second A.C. operating the choppers 108, 175 and 159, as illustrated in FIG. 3a, and the 60 cycle per second A.C. operating the servo motors 144 and 223, as illustrated in FIG. 3b is here assumed to be substantially the same source of A.C. or may be separate sources of A.C. but substantially in phase with each other, and are used as a reference to determine the electrical phase of the A.C. passed by the capacitor 113, 183 and 166, as described below.

Let it be assumed, for example, that arm 111 connects with contact 109 and then with contact 107. Let it also be assumed that the potential at contact 109 is a greater positive value than the potential at contact 107. Under such conditions the wave form *a* may represent the A.C. wave passed by capacitor 113. This condition may indicate that the voltage at arm 115 must be reduced to equal the potential at capacitor 44a and therefore that arm 115 must be repositioned to a lower position on resistance 114 of potentiometer 114/115.

If on the other hand the value at contacts 107 and 109 were reversed, that is that the potential at contact 109 were of a less positive value than the potential at contact 107 then the wave form *b* may represent the A.C. wave passed by capacitor 113. This condition may indicate that the voltage at arm 115 must be increased to equal the potential at capacitor 44a and therefore that the arm 115 must be repositioned to a higher position on resistance 114 of potentiometer 114/115.

Thus the phase of the A.C. passed through capacitor 113, with respect to the phase of the reference A.C. is employed to drive the motor in the desired direction to reposition the arm to a position where the potential at the arm 115 is substantially equal to the potential on capacitor 44a.

Returning momentarily to FIG. 1, it should be understood that when the output of block 19, which is the last car speed electrical storage, differs from the output of block 20, the last car speed mechanical storage, the null 26, fed by both outputs, is not attained. As block 20 is being adjusted so that its output will be equal to the output of block 19 (prior to attaining the null) the output of block 20 is being fed via lead 35 to the deviation unit, block 13, into block 40. The signal fed via lead 35 is modified by block 40 and passed by "not" gate 43 to block 44, the new arithmetic average speed electrical stor-

15

age. Thus as block 20 is being adjusted to a new value the block 44 is also being adjusted to a new value which equals the value of the output of block 20 somewhat modified by block 40.

When the outputs of block 19 and block 20 are substantially equal a null between the two outputs is attained. At this moment the output of block 20 represents the speed of the last car (L.C.), and this output has, via lead 35, been applied to and modified by the deviation unit so that the output of block 44 now represents a new arithmetic average speed (A.A.).

With the occurrence of the null between the outputs of blocks 19 and 20 a relay, for example AIN, shown in block 26 is operated.

Generally, the relay AIN, may control the pull-in circuit for a relay Ab, for example, shown in gate, block 24, after which the relay Ab holds through its own contacts.

The coil of relay DX, shown in FIG. 3a, may be connected in parallel with the coil of relay Ab so that as relay Ab is energized relay DX is also energized.

Thus the relays Ab and DX may be controlled by relay AIN for initial energization but each thereafter hold through contacts of relay Ab, independent of relay AIN.

Relay DX, as shown in FIG. 3a controls two sets of contacts. The block 43 represents one set of contacts while the block 45 represents the second set of contacts.

With relay DX deenergized, that is prior to reaching a null between blocks 19 and 20, the contact in block 43 is closed to permit passage of the L.C. signal from lead 35 through block 40, through gate 43 to block 44, for adjustment of the new A.A., while the contacts in block 45 are closed to complete a ground connection to short out the output of the servo amplifier and, in effect nullify the effect of the servo amplifier on the servo motor.

When the null is attained the relay AIN is operated to operate relay Ab and DX. With relay DX energized "not" gate 43 is opened to stop charging or adjusting of block 44 and gate 45 is opened to permit adjustment of block 46 breaking or opening the connection to ground thus permitting the servo amplifier to apply its output to the servo motor and thus drive block 46 to a new position according to the value of block 44.

Thus it may be seen that although the "not" gate 43 and gate 45 both are illustrated in FIG. 3a as break contacts on relay DX the functional operation of the two gates are opposite to each other.

Returning to FIG. 3, with a difference signal between the values applied to the contacts 107 and 109 of chopper 108 the varying potential on moving arm 111 is passed through capacitor 113 as an A.C. This A.C. signal is applied through resistance 123 to ground.

The A.C. potential is applied to grid 124 of tube 125, the tube 125 being of the conventional triode type generally employed for amplification. The plate circuit of tube 125 is coupled through resistance/capacitance coupling to the grid of a second stage of amplification, including tube 126. The amplified A.C. signal is passed through coupling capacitor 127 to junction 101 and when contact 45 is open, the signal is applied through coil 128 to ground. The A.C. signal applied to coil 128 causes induced current in coil 129 of transformer 128/129.

The induced A.C. potential in coil 129 is applied to the grids 130 and 136 causing alternate conduction of the associated tubes 133 and 137 respectively so that when tube 133 is conducting tube 137 is non-conducting.

The plate circuit of tube 133 follows via lead 138 to FIG. 3b to lead 139 to the lower tap on coil 140 of servo motor 144. The center tap of coil 140 is connected to B+ voltage of the order of +300 volts D.C. for example. The cathode 134 of tube 133 is connected to ground through cathode load resistance 135.

The tubes 133 and 137 are illustrated as beam power tubes connected for push-pull amplification.

The plate circuit of tube 137 follows via lead 145 to

16

FIG. 3b to lead 146 to the upper tap on coil 140 of servo-motor 144 and through to the center tap to B+ supply. The cathode 147 of tube 137 is connected to ground through cathode load resistance 135.

5 The coil 148 of servo-motor 144 is connected to a 60 cycle per second A.C. source which is substantially in phase with the 60 cycle per second A.C. source operating the chopper 108.

The servo-motor 144 represents a phase sensitive, two phase motor which rotates clockwise or counterclockwise according to the phase relation of the electrical current in coil 140 with respect to the electrical phase of the reference electrical current in coil 148. These currents are normally displaced 90 degrees in phase with respect to each other and since the coil 148 is connected across the A.C. line the 90 degree displacement is secured on the other coil 140, through the combination of the capacitor connected across it, the tuning capacitor associated with windings 128 and 129 of the coupling transformer, and through the mechanical phase lag of the armature 111 with respect to its driving coil in chopper 108 which is driven from an A.C. essentially in phase with the A.C. across coil 148.

An indicator lamp L1 which is connected across coil 140 is illuminated when the motor 144 is operating.

Thus according to the phase relationship of the signal passed through capacitor 113, relative to the phase of the A.C. operating the chopper 108 the phase sensitive servo motor 144 is driven clockwise or counterclockwise to re-position the arm 115 until the voltage at arm 115, applied through junction 110, lead 116, impedance 117 and resistance 118, to contact 109 is substantially equal to the voltage applied to contact 107 from capacitor 44a.

When the two potentials are substantially equal the 35 output of the chopper is substantially zero, thus the signal on grid 124 is reduced to substantially zero.

Now the new arithmetic average speed value is stored on the potentiometer 114/115 with the new value represented by the voltage at arm 115.

40 The arm 115 is mechanically connected to the motor 144 by suitable gearing and is driven in the desired direction according to the electrical phase relationship between the current in the coils 140 and 148. The arm 151 is linked mechanically to arm 115 so that as arm 115 is positioned on the resistance 114 the arm 151 is positioned on the resistance 152 corresponding to the position of arm 115.

45 A D.C. voltage, of the order of +10 volts for example, is applied at terminal 160 to the resistance 114 of potentiometer 114/115 to ground.

The voltage at arm 115 is applied via lead 42 to junction 110 and through to the contact 109 of chopper 108 as previously described and also applied to the resistance 152 of potentiometer 151/152. The arm 151 is positioned on resistance 152 according to the position of arm 115 relative to resistance 114, as previously described and the voltage at arm 151 is equal to the square of the fractional position of arm 115 on the resistance 114.

50 For example, with +10 D.C. volts applied through the resistance 114 of potentiometer 114/115 and an arithmetic average speed of 50 miles per hour, represented on a voltage scale of 0 to +10 volts equal to 0 to 100 miles per hour, the arm 115 will be positioned at the $\frac{1}{2}$ position interim the ends of the resistance 114. Thus 55 5 volts or $\frac{1}{2}$ the applied voltage of 10 volts will be picked off the resistance 114 by arm 115 and will represent the arithmetic average speed of 50 miles per hour. The 5 volts at arm 115 will be applied through the resistance 152 of potentiometer 151/152 to ground. The arm 151

60 which is positioned on the resistance 152 corresponding to the position of arm 115 on resistance 114, will also be positioned at the $\frac{1}{2}$ position intermediate the ends of resistance 152. Thus with 5 volts applied through resistance 152 from arm 115, the voltage at arm 151 will be $\frac{1}{2}$ the applied voltage of 5 volts or 2.5 volts above

ground and will be the equal to $\frac{1}{4}$ of the entire original input voltage of +10 volts and will be equal to the square of the fraction of the position of the arm 115, the square of $\frac{1}{2}$ which is ($\frac{1}{4}$).

With the voltage at arm 151 representing the arithmetic average speed squared, $\overline{A.A.}^2$, the voltage is applied via lead 155 to FIG. 3a to resistances 156 and 157 to contact 158 of chopper 159.

The resistors 156 and 157 and chopper 159 are part of the subtracting circuit illustrated in block form in FIG. 1 and labeled 48.

The voltage representing the root mean square speed squared, $\overline{R.M.S.}^2$, is applied to lead 36 from the speed averaging unit and was determined from the same number of cars as the arithmetic average speed squared ($\overline{A.A.}^2$) the number of cars being determined by the setting of arm 121 of adjustable resistance 120. The voltage representing the $\overline{R.M.S.}^2$ is fed via lead 36 through resistance 164 and 165 to contact 161 of chopper 159.

Since the root mean square speed squared, $\overline{R.M.S.}^2$, value represents an average value of the squared speeds and the arithmetic average speed squared $\overline{A.A.}^2$, value represents the squared average of the speeds, and both the root mean square (R.M.S.) value and the arithmetic average (A.A.) value are based on the same vehicle speeds, it may be assumed that the $\overline{R.M.S.}^2$ value will be higher than the $\overline{A.A.}^2$ value to the extent that there is any differences in the speeds of the cars from which the measurement is taken.

The difference voltage between the $\overline{R.M.S.}^2$ value and the $\overline{A.A.}^2$ value will be sensed at the capacitor 166 as the moving contact 162 of chopper 159 alternately connects between contacts 158 and 161. The difference voltage in the form of an A.C. will pass through capacitor 166 and through resistance 167 to junction 168.

The A.C. voltage applied to junction 168 from chopper 159 is opposed by an A.C. voltage applied to junction 168 via resistor 169 from moving contact 173 of chopper 175.

The A.C. voltage passed by moving contact 173 is the difference voltage between the potential at contact 176, and the potential value at contact 174. The voltage at contact 176 is essentially at zero, with respect to ground, which zero potential is obtained by adjustment of arm 178 on the potential divider network 177 between a positive D.C. of the order of +155 volts and a negative D.C. of -15 volts, for example, with ground connected in the network.

The voltage at contact 174 is applied from the arm 185 of potentiometer 184/185 in FIG. 3b the deviation squared potentiometer, through lead 186 and resistor 179 and modified somewhat by the voltage divider circuit 187 to the contact 174 depending on the position of adjustable arm 199.

It will be observed that of the two voltages applied to contacts of chopper 175 that applied to contact 176 is normally lower than that applied to contact 174 and of the two voltages applied to contacts of chopper 159 that applied to contact 161 is normally higher than that applied to contact 158; and that the moving contacts 173 and 162 will operate in unison and connect respectively with contacts 176 and 161 at the same time. Thus the potentials applied to junction 168 will be 180° out of phase with each other and when the A.C. voltages at the moving contacts 173 and 162 are substantially of the same amplitude the potential at junction 168 will be substantially zero since the two applied A.C. potentials are equal and opposite and effectively cancel each other.

When the two A.C. voltages are unequal in amplitude an A.C. signal equal in amplitude to the difference in magnitude of the two voltages is passed through capacitor 188 to the grid of the power amplifier 189. The signal output of tube 189 is amplified successively by triodes 193 and 194 and the amplified output is applied through coupling capacitor 195 and fed through coil 196

to ground. Induced current in the other coil 197, of the coupling transformer provides a potential to the grids 201 and 207 of beam power tubes 204 and 208 respectively. These tubes are connected for push-pull power amplification.

The preamplifier and two stage servo amplifier section are arranged for high gain amplification to provide for amplification of very small amplitudes of A.C. at junction 163 so that very small differences between the A.C. at chopper 173 and the A.C. at chopper 159 may be sensed and amplified. Therefore with such high gain amplification an A.C. of a relatively large amplitude at junction 163 may produce an excessively strong signal induced in coil 197. The diodes 210 and 211 are provided to reduce any excessively strong signal to a maximum limit so as to prevent overdriving of the amplifier output stage.

Since the choppers 175 and 159 are operated by the same A.C. power, the electrical phase of the A.C. potential at junction 168 and the phase of the A.C. operating 20 the choppers 175 and 159 determines the direction of drive of the motor 223 in FIG. 3b in a similar manner as that described for directional control of the motor 144 with respect to the relation between the A.C. at capacitor 113 and the A.C. operating chopper 108.

The plate circuit of the tube 204 includes lead 214 to FIG. 3b, to the lower tap of coil 216 to the center tap of coil 216, lead 217 to the B+ supply. The cathode of tube 204 is connected to ground via resistance 205.

The plate circuit of the tube 208 includes lead 218 to 30 FIG. 3b, to the upper tap of coil 216 to the center tap of coil 216, lead 217 to B+ supply. The cathode of tube 208 is connected to ground via resistance 205.

The A.C. in coil 220 is an A.C. substantially in phase with the A.C. operating the choppers 175 and 159, and 35 the A.C. in the coil 216 is related in phase to the A.C. at junction 163. Thus according to the phase relationship between the A.C. in coil 220 and the A.C. in coil 216 the servo motor 223 will be caused to rotate either clockwise or counterclockwise. An indicator lamp L2, which is connected across the coil 216 is illuminated when the motor 223 is operating.

The arm 185 of the potentiometer 184/185 is suitably geared to the motor 223 so that the arm 185 is positioned on the resistance 184 so that the voltage at arm 185, which 45 is applied via lead 186 to FIG. 3a, through resistor 179 to contact 174, may be above ground zero, in a positive direction, the same amplitude as the magnitude of the difference between the two voltages applied to contacts 158 and 161 of chopper 159.

The arm 185 may be mechanically connected to arm 225 so that arm 225 is positioned on the resistor 224 of potentiometer 224/225 corresponding to the position of arm 185 on the resistor 184.

This arrangement is similar to the arrangement of the 55 potentiometers 114/115 and 151/152 and their associated D.C. supply. As for example, a D.C. supply of substantially the same amplitude, +10 volts, is applied through resistor 224 and the voltage at arm 225 is applied through resistor 184. With the positions of arms 225 and 185 60 corresponding to each other the fraction of the voltage at arm 185, relative to the entire applied voltage (+10 volts), is equal to the square of the fractional position of the arm 225 relative to its position on the resistor 224. Thus the potentiometer 184/185 may be considered 65 the deviation squared mechanical storage and potentiometer 224/225 may be considered the square root of deviation squared or deviation mechanical storage with the output voltage at arm 225 via lead 230 corresponding to deviation.

70 Thus the arithmetic average speed squared ($\overline{A.A.}^2$) of a predetermined number of vehicle speeds is subtracted from the root mean square speed squared ($\overline{R.M.S.}^2$) of substantially the same vehicle speeds in a chopper 159. 75 The result of the subtraction, a voltage representing the

remainder which is the square of the speed deviation, is matched by the output of a second chopper 175, the output of chopper 175 being referenced to a desired zero approximating ground. The magnitude of the output of chopper 175 above zero, is representative of the voltage at arm 185 of squaring potentiometer 184/185. The square root of the value at arm 185 is represented at arm 225. Therefore speed deviation, which is the square root of the remainder of the subtraction of $A.A.^2$ from the R.M.S.² is represented by the output voltage at arm 225 which output may be applied via lead 230 to a meter 232, which may be calibrated in terms of speed deviation, or to a terminal 232a.

Connected to the output lead 232a is the grid of a tube 235 so that the voltage output representing deviation may be applied to such grid. In the plate circuit of tube 235 is a relay 236 which may be energized when tube 235 passes current. Adjustable cathode bias of tube 235 is provided so that the tube may provide current to energize the relay only above a certain value of deviation, as desired.

At and above certain values of deviation, as adjusted by adjustment of the cathode bias, the tube 235 will pass current causing energization of relay 236 which relay will then close its normally open contact 237 which may complete a circuit to do work or operate an alarm, as desired.

The output at arm 115, the arithmetic average speed may be applied to a meter 228 or to a terminal 228a.

Thus on meter 228 one may read the arithmetic average speed and on meter 232 one may read the speed deviation.

In FIG. 3b the adjustable resistance 120 is provided so that selection may be made to average various number of vehicles through changing the position of selector switch 121.

In FIG. 3a a potential divider 187 is provided with adjustable selector 190 to provide selection of a percentage of the signal applied contact 174 of chopper 175. This provides for selection of difference calibration on the meter 232.

Considering the foregoing specification and accompanying drawings, alternate forms of the present invention have been presented thus accomplishing the stated and other objects. Obviously other modifications, substitutions and rearrangement of parts may be resorted to without departing from the spirit of the invention.

I claim:

1. A traffic speed deviation computer including means for sensing the individual speeds of a series of vehicles having variable speed and variable time spacing, first means for providing a first output representing the square of the root mean square of such speeds sensed by said sensing means irrespective of variation in time spacing between successive individual speeds, said first means including means for varying the value of the first output in proportion to the difference between said first output and each particular speed signal and in proportion to a predetermined number of such vehicles, and second means for providing a second output representing the square of the arithmetic average of such speeds sensed by said sensing means irrespective of variation in time spacing between successive individual speeds, said second means including means for varying the value of the second output in proportion to the difference between said second output and each particular speed signal and in proportion to said predetermined number of such vehicles, means for receiving said first and second outputs and deriving therefrom an output representing the difference between said first and second outputs, and means for deriving the square root of said difference output to provide an output representing the average deviation of the sensed speeds from the average of said predetermined number sensed speeds.

2. A traffic speed deviation computer as in claim 1 and

including means for indicating said deviation on a visual scale.

3. A traffic speed deviation computer as in claim 1 and including means controlled by said deviation output for providing a further output in response to said deviation output exceeding a predetermined value.

4. In a traffic speed deviation computer, means for continuously sensing the individual speeds of individual vehicles successively passing a point along a roadway, means for providing a first electrical output representing the square of the root mean square of such speeds of a predetermined number of vehicles having most recently passed said point and sensed by said sensing means irrespective of variation in time spacing between successive individual speeds, means for providing a second electrical output representing the square of the arithmetic average of such speeds of said most recently passed predetermined number of vehicles sensed by said sensing means irrespective of variation in time spacing between successive individual speeds, means for receiving said first and second outputs and continuously deriving therefrom an output representing the difference between said first and second outputs.

5. A traffic speed deviation computer including means for continuously sensing the speeds of a series of vehicles and developing therefrom an electrical signal representing the squared root mean square of such speeds, means for continuously sensing the speeds of said series of vehicles and providing another electrical signal representing the square of the arithmetic average of such speeds, means for storing each of said electrical values, said means providing electrical signals representing the squared root means square and squared arithmetic average of such speeds including means for varying its individual stored value in proportion to a predetermined number of vehicles, means for continuously sensing the difference between said stored electrical signals to provide an electrical signal representing the square of the deviation of such speeds and means for deriving the square root of the last named signal to provide an output representing the deviation of such speeds.

6. A traffic speed deviation computer as in claim 5 and in which said last named output is an electrical value and said computer includes a meter for indicating said electrical value in terms of deviation of speed.

7. A system for continually computing the root mean square deviation of a continually varying series of a predetermined number of speed values representing the speeds of a continually varying series of vehicles in traffic, including means for receiving said speed values and determining a mean square average of said values and providing an electrical output representing said average, means for receiving said same speed values and determining an arithmetic average of said values and providing an electrical output representing the last named average, means for squaring said last named average output, means for continually comparing said squared last named average output with said mean square average output to continually derive an electrical output representing the difference between said average outputs, means for deriving the square root of the last named electrical output to provide an output representing said deviation.

8. A system as in claim 7 and including means for adjusting said averaging means to vary said predetermined number of vehicles and corresponding number of received speed values for such averaging.

9. A system as in claim 8 in which said adjusting means are cooperatively adjusted for the respective squared average and average square signals whereby the last named signals will be averaged on corresponding numbers of vehicles.

10. A system as in claim 7 in which said means for providing said squared average and average square signals are recycled in response to each new received speed value to readjust the last two named signals for each said new

received speed value whereby said deviation output will be substantially continuously adjusted for the latest desired number of vehicles.

11. A system as in claim 7 and including means for adjusting the deviation output in relation to the received speed value.

12. In a system for determining the average deviation of a number of values from an average of such values and having means for sensing the individual values in succession and developing therefrom electrical signals representing each latest individual value and the square of the root mean square of the latest predetermined number of said values respectively irrespective of variation in time spacing between successive individual values, the combination of means for receiving each said latest individual value and developing an electrical signal representing the square of the arithmetic average of said latest predetermined number of values irrespective of variation in time spacing between successive individual values, means for comparing said squared root mean square electrical signal and said squared arithmetic average electrical signal to derive a further electrical signal representing the difference between the compared signals, and means for developing from said further signal an electrical output signal representing the square root of said difference signal to represent said deviation.

13. A combination as in claim 12 in which said comparing means includes a chopper having alternate inputs connected to the respective compared signals and an output alternating between said inputs, and a capacitor in series with said output to provide an alternating current output therefrom, and means controlled by said alternating current output for providing said further electrical signal.

14. A combination as in claim 12 and in which said comparing means includes a chopper having two inputs connected to the respective compared signals and an output alternately connected to its respective inputs and a capacitor in series with its output, and in which said square root deriving means includes two potentiometers having stationary resistance elements and contact arms mechanically linked to be movable together over the respective resistance elements, the resistance element of one of said potentiometers being connected across a predetermined direct current voltage and the other resistance element being connected between the arm of said one potentiometer and one end of its resistance element, a second chopper having two inputs one of which is connected to the arm of the second of said potentiometers and the other input of which is connected to a reference direct current voltage for setting zero reference with respect to the output voltage on the last named contact arm, and said chopper having an output alternately connected to its respective inputs, a servo-amplifier having an input and output, impedance means interconnecting the outputs of the respective choppers to provide an alternating current input to said servo-amplifier of amplitude substantially proportional to the difference between the outputs of said choppers and whose phase reverses for reversal of relative amplitude of the outputs of said choppers, and a servomotor controlled by said servo-amplifier to move said contact arms so that the output voltage of the arm of said other potentiometer with respect to the zero reference corresponds with the output of the first chopper and thus to the difference between the average squared signal and the squared average signal and thus to the square of the deviation, and the output of the arm of the said one potentiometer represents the square root of said difference and thus the deviation.

15. In a system for determining the deviation of the latest predetermined number of a continuing random spaced series of varied electrical values, means for receiving each said value and initiating a computing cycle therefrom, means for storing the latest said value in said

cycle in place of the previous said value, and providing an electrical output therefrom, means for squaring said latest value and storing said squared value in said cycle, means for storing the average of the squares of the latest predetermined number of said values from the previous said cycle, means for readjusting said stored squared average by a fraction of the difference between the previous stored squared average value and the latest stored squared individual such value based on the said predetermined number to provide and store the new latest squared average of the values, means for developing and storing an arithmetic average of said latest predetermined number of individual values and which said arithmetic average is readjusted by a fraction of the difference between the previous stored arithmetic average and the new latest individual stored value, means for squaring said stored arithmetic average and storing said squared average to complete the cycle, means for comparing the two stored squared averages to derive and store the difference between them as the square of the deviation, and means for deriving and storing the square root of the last named difference as representing the deviation.

16. Electrical apparatus for substantially continuously determining the root mean square deviation of speeds of vehicles proceeding past a given location along a traffic lane having variable speed and variable time spacing, including means for sensing the individual speeds of said vehicles, means for deriving from the speeds so sensed a first electrical signal representing the square of the root mean square of the speeds of the latest predetermined number of said vehicles, means for deriving from the speeds so sensed a second electrical signal representing the square of the arithmetic average of the same latest predetermined number of said vehicles, means for deriving from said first and second signals a third electrical signal representing the difference between said first and second signals, and means for deriving from said third signal an output signal representing the square root of said third signal, whereby the last named output signal will represent said deviation of speeds for said latest predetermined number of vehicles.

17. A traffic speed deviation computer including means for continuous sensing of the individual speeds of each of the successive vehicles passing a point along a roadway, means for providing a first electrical output continuously representing the square of the root mean square of the speeds of a group of vehicles most recently having passed said sensing point, means for providing a second electrical output representing the square of the arithmetic average of the speeds of said most recent vehicles, means for deriving an output continuously representing the difference between said first and second output signals, and means for deriving the square root of said difference signal to provide an output representing average vehicle speed deviation.

18. A combination as in claim 17 in which said squared root mean square and arithmetic averaging means include means for varying their output in response to each vehicle inversely in proportion to the number of vehicles desired to be averaged.

19. A combination as in claim 17 in which said averaging means include means for averaging over an adjustable number of vehicles.

20. A combination as in claim 17 in which at least one of said averaging circuits includes a servo motor, servo amplifier, chopper and potentiometers connected to derive the potentiometer to balance at a null point and to derive the squared function from the tap on one of the potentiometers.
